UNITED STATES PATENT OFFICE.

BENJAMIN ORMAN, OF BELVEDERE, ENGLAND.

AUTOMATIC FIREARM.

1,128,180.

Specification of Letters Patent.

Patented Feb. 9, 1915.

Application filed June 23, 1913. Serial No. 775,305.

To all whom it may concern:

Be it known that I, BENJAMIN ORMAN, a subject of the King of Great Britain, residing at 34 Gordon road, Belvedere, in the county of Kent, England, have invented certain new and useful Improvements in Automatic Firearms, of which the following is a specification.

This invention relates to automatic firearms particularly pistols, of the kind in which the barrel and the bolt recoil for a short distance together against the resistance of springs and then become unlocked by the movement of a rotary bolt head 10 whereupon the barrel returns to the firing position under the reaction of its spring while the bolt continues to recoil, thus opening the breech effecting the extraction and ejection of the empty cartridge case and 15 cocking the hammer, after which the bolt is returned by the reaction of its spring and in advancing to close the breech pushes a fresh cartridge from a magazine into the barrel and by the reverse rotary movement 20 of the bolt head becomes re-locked to the barrel ready for the next discharge. The bolt comprises two principal parts, one the body and the other a rotary quick threaded stem having at its outer end or head the 25 usual locking segments or interrupted threads for engaging with corresponding cavities or threads in the barrel extension, these two parts being so arranged that the angular movement of the stem necessary for 30 locking and unlocking the bolt to and from the barrel is effected by the body sliding on the stem during the final closing and the initial opening of the breech. According 35 to my invention the bolt is so constructed 40 and arranged that during the recoil of the barrel the rearward movement of the body of the bolt is accelerated by suitable means so that the said body will move faster than the stem, and in so doing will travel along 45 the latter and cause it to turn in the reverse direction for thus effecting the disengagement of the locking segments and permitting the bolt to perform its rearward movement to open the breech, while the barrel 50 turns to the firing position. As the bolt advances to close the breech the movement of the stem is arrested by its head coming against the barrel and the body continues to advance independently of the stem with 55 the result that the stem turns in the body and effects the locking engagement with the

barrel. The rearward extension of the barrel may have a pair of parallel rearwardly extending bars serving as guides for the bolt and these bars may be suitably shaped for controlling the escape of the cartridge from the magazine under the influence of the spring lifter, so that the uppermost cartridge of the magazine will be permitted to leave the magazine as the barrel regains its firing position after recoil and assume the proper position for being introduced into the barrel by the bolt as it advances in closing the breech. The extractor is preferably made integral with a spring collar or clip 70 which is adapted to be sprung into position around the stem immediately behind the locking head, without requiring any screw pins or the like for holding it in position.

In order that the said invention may be 75 clearly understood and readily carried into effect, the same will now be described more fully with reference to the accompanying drawings, in which:

Figure 1 is a longitudinal section of an 80 automatic pistol constructed according to my invention. Fig. 2 is a fragmentary sectional elevation showing a cartridge in the loading position ready to be pushed into the barrel by the bolt as it advances to close the breech. Fig. 3 is a sectional plan on the line 1—1 of Fig. 1 with the barrel and bolt removed. Fig. 4 is a sectional elevation showing the means employed for obtaining the aforesaid accelerated movement of the body of the bolt 90 during recoil. Fig. 5 is a sectional elevation, Fig. 6 a plan and Fig. 7 an underside view of the bolt detached from the pistol. Fig. 8 is an end view of the bolt as seen from the left of Fig. 5. Fig. 9 is a cross section on the 95 line 2—2 of Fig. 5. Fig. 9a is a view showing the extractor detached from the stem of the bolt. Fig. 10 is a plan of the barrel extension and its rearwardly extending bars and Fig. 11 is an end view as seen from the 100 right of Fig. 10.

In all these figures like letters of reference indicate similar parts.

A is the barrel, and B the bolt.

C' C² are the recoil and return springs for 105 the bolt and barrel respectively the said springs being of spiral form and carried by rods c' c² which project inwardly from the rear wall of the breech casing C which is detachable. The springs C' extend into holes 110 2 formed in the body of the bolt, each of which holes is formed with a reduced por-

tion as shown in Fig. 1, thus providing a shoulder against which the end of the spring abuts. The barrel extension a' is provided with rearwardly extending bars a^3 provided 5 with holes 3 which receive the ends of the rods c^2 while the springs C^2 abut against the rear surfaces of the bars.

D is the firing pin.

E is the hammer and E' the main spring. 10 F is the sear and G is the trigger.

H is the stock or handle of the weapon which is adapted to contain the magazine J. The stock H is provided with a platform H' having an opening 5 within which a 15 hammer releasing member is adapted to slide. This member consists of a front plate 6, a bar 7, and a rear plate 8. The trigger G is provided with a nose 4 which engages with an opening in the front plate 6, and a 20 spring 10 abuts at one end against the plate 6 and at its other end against a downwardly extending flange 11 formed integral with the platform H', so that when the trigger is pulled, the hammer releasing member is 25 moved forward and when the trigger is released the member is returned to its normal position by the spring 10. Pivoted to lugs on the rear plate 8 is a catch 9 which is 30 pressed by a spring into engagement with the sear F as shown in Fig. 1. It will thus be seen that when the releasing member is moved forward by means of the trigger, the sear F will be pulled away from the hammer, which is thus released.

35 The barrel A is adapted to slide on the upper surface or platform H' of the stock H, for which purpose the barrel extension a' is formed with longitudinal grooves a^2 engaging with the edges of the said platform. The rearwardly extending bars a^3 of the barrel extension a' serve as guides for the body of the bolt which is flanged at b^3 , b^3 to engage with the said guides and slides thereon without turning about its axis. 40 These guide bars a^3 are also so formed that they operate to control the escape of the cartridges from the magazine as hereinafter explained.

The body of the bolt B carries the rotary 50 stem b^4 which is formed with a quick thread on its outer surface engaging with a corresponding internally threaded portion b^5 in the body of the bolt; the outer end or head of the said stem having the usual locking 55 segments b^6 for engaging with corresponding cavities a^4 in the barrel extension a' when the breech is closed and angular movement imparted to the said stem (Fig. 11). In order to effect the opening of the breech 60 during recoil angular movement is imparted to the said stem by accelerating the movement of the body of the bolt relatively to the stem, which movement is obtained in the example shown, by means of an arm or lever 65 a^5 pivoted at a^6 to the barrel extension so as

to move with the barrel, the said lever being housed in a cavity a^5 . This lever has a toe piece a^7 which works in a slot h formed in the platform H' (Fig. 3) and on recoil of the barrel comes against the rear end of the 70 said slot whereupon the lever is caused to turn about its pivot in a direction to strike the body of the bolt and forcibly project it rearwardly away from the barrel with an accelerated movement. Instead of arranging the toe piece a^7 to strike the end of the aforesaid slot it may be arranged to strike a shoulder or projection on the platform. This accelerated movement of the bolt body 75 causes the stem to turn into a position to unlock its head from the barrel extension with the result that the bolt body and the stem continue to move rearwardly together independently of the barrel and thus open the breech. On the return of the barrel to the firing position the said lever a^5 will return to its original position by the action of a spring a^8 or by the aforesaid toe piece coming against the forward end of the said slot h , or against a fixed shoulder or projection. 80

The body of the bolt B is shown provided with pins or projections b^7 extending through longitudinal slots c^3 c^4 , formed in the opposite sides of the detachable casing C, (Fig. 4), the said pins or projections being provided with heads of suitable shape 95 to enable them to be conveniently clasped between the finger and thumb of the user when it is desired to operate the bolt by 100 hand.

The aforesaid guide bars a^3 of the barrel extension are so formed that they lie somewhat closer together at their rear than at their forward parts where they join the barrel extension (Fig. 10) so that a cartridge in leaving the magazine cannot escape bodily upward but assumes an inclined position with its nose directed toward an incline a^9 leading to the cartridge chamber and its rear end slightly projecting into the path of the bolt. As the said bolt advances to close the breech the locking head b^6 will meet the projecting part of the base of the cartridge and push the latter forward up the said incline a^9 into the cartridge chamber (Fig. 2). One of the said guide bars is formed with the cartridge ejector, which is in the form of an inwardly projecting lug a^{10} against which the base of the empty cartridge cases will strike as they are withdrawn from the barrel by the extractor b^8 during the recoil movement of the bolt in opening the breech. In order to enable the ejector to reach the base of the cartridge case during the recoil the underside of the bolt body is formed with a slot b^{10} and the bolt stem and its head are provided with a groove b^9 . 110

The firing pin D extends longitudinally 115

through the body of the bolt B and is surrounded by the stem b^4 which is made hollow to receive it. The rear end of the firing pin is secured to a block d (see Fig. 5) which is struck by the hammer E. The said firing pin has only a limited movement which is controlled by a transverse pin b^{11} engaging a slot d' formed in the block d . The nose or point of the firing pin is normally prevented from protruding beyond the face of the locking head of the bolt stem by means of a spiral spring d^2 which is located in a cavity in the stem b^4 immediately in front of the block d , so that until the block d of the said firing pin is struck by the hammer E and caused to move outward against the resistance of the said spring d^2 the firing pin cannot come into contact with the primer of the cartridge in the barrel and unintentionally fire the weapon.

The extractor forms part of a spring collar or clip b^{12} which can be sprung into position around the stem b^4 immediately behind the locking head without requiring any screw pins or the like for holding it in place as aforesaid. The stem may have an annular groove or recess for the reception of the said clip and a longitudinal groove is formed through the said head for the claw of the extractor to project through. When the stem b^4 rotates in opening and closing the breech, the extractor rotates with it and the claw of the extractor slips around the flange of the cartridge.

Contiguous to the trigger is a pivoted safety catch K which is provided with a thumb piece k to enable it to be turned into a more or less horizontal position whereupon it comes into contact with the trigger G and prevents the latter from being pulled; in assuming this position it also becomes disclosed to view and thereby provides a visible indication as to whether the weapon is in the safety condition or not.

Although I have described my invention more particularly with respect to pistols I wish it to be understood that it is also applicable to rifles.

What I claim and desire to secure by Letters Patent of the United States is:—

1. In an automatic firearm the combination of a bolt comprising a body portion and a rotary quick threaded stem carrying the locking head with means whereby during the recoil of the barrel the rearward movement of the body portion of the bolt is accelerated to cause the said body to move faster than the stem so that the stem is turned in the proper direction to unlock it from the barrel.

2. In an automatic firearm, the combina-

tion with a recoiling barrel and a bolt comprising a body portion and a rotary quick threaded stem carrying a locking head, of means whereby during the recoil of the barrel the rearward movement of the body portion of the bolt is accelerated to cause the said body to move faster than the stem so that the stem is turned in the proper direction to unlock it from the barrel, means for returning the barrel to the firing position, and means for returning the bolt independently of the barrel.

3. In an automatic firearm, the combination with a recoiling barrel and a bolt comprising a body portion and a rotary quick threaded stem carrying a locking head, of means connected to the barrel and unconnected with the bolt for imparting to the latter an accelerated motion during the recoil of the barrel whereby the stem is caused to turn and become unlocked from the barrel.

4. In an automatic firearm, the combination with a recoiling barrel and a bolt comprising a body portion and a rotary quick threaded stem carrying a locking head, of a lever pivoted to the barrel and adapted during the recoil of the barrel, to strike the body of the bolt so as to give it an accelerated movement whereby the stem is turned and unlocked from the barrel, means for returning the barrel to the firing position, and means for returning the bolt independently of the barrel.

5. In an automatic firearm, the combination with the barrel extension of rearwardly extending bars which are closer together at their rear ends than at their forward ends whereby a cartridge passing upwardly between them is tilted so that the nose of the bullet projects upward, and an inclined surface formed on the barrel extension and between the said bars for guiding the cartridge into the barrel.

6. In an automatic firearm the combination with the bolt stem of a cartridge extractor provided with means whereby it can be sprung into position around the bolt stem immediately behind the locking head.

7. In an automatic firearm, the combination with a bolt stem of a cartridge extractor forming part of a spring clip which is sprung into position around the bolt stem immediately behind the locking head.

In testimony whereof I affix my signature in presence of two witnesses.

BENJAMIN ORMAN.
